FEEDING DEVICE FOR STORAGE COUNTING MECHANISMS IN CALCULATING MACHINES

Application filed April 7, 1930, Serial No. 442,427, and in Germany April 15, 1929.

This invention relates to a feeding device for the storage counting mechanisms in calculating machines in which these counting mechanisms in a manner known in itself 5 are arranged on the periphery of a rotatable drum, this drum being rotated about its axis under the influence of the paper carriage, as it jumps from column to column during the working operation, in such a way 10 that at each jump of the paper carriage the next counting mechanism moves into the working position.

The object of the invention is to construct the feeding device that serves for carrying 15 out the above-mentioned operation, that is to say, the device for intermittently locking and releasing the drum, which is set in rotation by spring power during the working operation, in such a way that an absolutely 20 reliable action is obtained and that disadvantageous shocks during the working operation and also during the return of the counting mechanism drum into the initial position or into a preceding position are obviated.

25 In order to attain this aim the feeding device for the storage counting mechanisms of calculating machines according to the present invention is essentially characterized by the fact that the stops provided on the 30 drum for the locking and release thereof in the working positions of the counting mechanisms are arranged step-wise in spiral form round the axis of the drum, and the necessary common abutment member for the stops, 35 for checking the movement of the drum, is displaced, under the action of the paper carriage, in a radial or approximately radial direction.

One constructional form of the feeding device according to this invention is shown in side elevation in the accompanying drawing.

On a bar *a* of the paper carriage of the calculating machine are arranged stops or 45 riders *b* at distances from one another corresponding to the division into columns of the form to be written.

By these stops *b*, when the jumping movement of the paper carriage from one column 50 to the next occurs, a five-pointed star wheel

c is rotated through a definite angle, and with it a vertical shaft *d* carrying the star wheel *c*. The shaft *d* transmits its rotation through toothed wheels *e* and *f* to a screw-threaded spindle *g*. By the rotation of the spindle *g* 55 a carriage *i*, mounted thereon by means of an internal screw thread, and guided vertically in a separate guide *h*, is axially displaced, and with it an abutment member *k*, transversely slidable therein, for the stepped 60 stops *m* arranged on a disc *l* on the counting mechanism drum, which is rotated by a spring *z*.

The transmission ratio between the toothed wheels *e* and *f* is so selected that when the 65 carriage jumps the abutment *k* moves out of reach of the stop *m* that was previously bearing against it and into the path of the next stop *m*, so that the rotation of the drum is checked in the succeeding counting mechanism position. 70

The abutment *k*, with the end *n* opposite to the face which engages with the abutment *m*, slides on a bar *o*, which bears against a member *p* consisting of resilient material, 75 such as india rubber, so that the impact of the stops *m* against the bar *k* is transmitted by the latter to the bar *o*, which bears against the cushion *p*. This arrangement prevents the impact of the stops from affecting the 80 spindle *g* by which the bar *k* is carried.

When the drum and the disc *l* are being returned in the direction of the arrow *x*, the spindle *g* tends to lower the carriage *i* with the bar *k* at a uniform speed. Since the disc *l* is not a smooth spiral curve, however, but is stepped, the peripheral surfaces of these steps *m* would at times exert an upward pressure upon the bar *k*. In order to prevent jamming, therefore, the spindle *g* is made capable of yielding in an upward direction, and a spring blade *q* is provided for the purpose of pressing it towards the disc. 90

In order to protect the drum against rebounding or recoil movements when the stops *m* strike against the abutment *k* during the working movement a pawl *r* is provided, which is so influenced by a spring *s* that it tends to rotate towards the left about its axis *t*, and bears with an arm *u* against a slide *v*, 100

operatively connected with the paper-carriage returning device.

During the working movement of the drum in the direction of the arrow y , this pawl r , in each of the stationary positions fixed by the stop m and the abutment k , snaps in the manner illustrated behind the associated counting mechanism shaft w and thus prevents any backward movement of the drum.

10 During the return of the drum to the initial position or a preceding position the slide v is shifted towards the right by the returning device, and consequently, by means of this slide, the pawl r is held by its arm u in the released position, that is to say, rocked towards the right.

What I claim is:—

1. A feeding device for the storage counting mechanisms arranged on the periphery of a drum rotatable under the control of a jumping paper carriage in calculating machines, comprising stops provided on the drum for the locking and release thereof in the working positions of the counting mechanisms, the said drum stops being arranged in spiral steps round the axis of the drum, a common abutment adapted to co-operate with the drum stops for checking the movement of the drum, the said common abutment being displaceable in a direction substantially radial in relation to the drum, and means adapted to be actuated from the paper carriage for displacing the common abutment relatively to the drum.

2. A feeding device for the storage counting mechanisms arranged on the periphery of a drum rotatable under the control of a jumping paper carriage in calculating machines, comprising stops provided on the drum for the locking and release thereof in the working positions of the counting mechanisms, the said drum stops being arranged in spiral steps round the axis of the drum, a common abutment adapted to co-operate with the drum stops for checking the movement of the drum, the said common abutment being displaceable in a direction substantially radial in relation to the drum, a rotatable screw spindle adapted when rotated to displace the common abutment relatively to the drum, and rider stops mounted on the paper carriage in positions corresponding to column subdivisions, the said rider stops being adapted to rotate the said spindle when the paper carriage executes its jumping movements.

3. A feeding device for the storage counting mechanisms arranged on the periphery of a drum rotatable under the control of a jumping paper carriage in calculating machines, comprising stops provided on the drum for the locking and release thereof in the working positions of the counting mechanisms, the said drum stops being arranged in spiral steps round the axis of the drum, a common abutment adapted to co-operate with the

drum stops for checking the movement of the drum, the said common abutment being displaceable in a direction substantially radial in relation to the drum, a rotatable screw spindle adapted when rotated to displace the common abutment relatively to the drum, a rotatable shaft, toothed wheels for transmitting motion from the said rotatable shaft to the screw spindle that displaces the common abutment, a star wheel secured to the rotatable shaft, and rider stops mounted on the paper carriage in positions corresponding to column subdivisions, the said rider stops being adapted to rotate the star wheel when the paper carriage executes its jumping movements.

4. A feeding device for the storage counting mechanisms arranged on the periphery of a drum rotatable under the control of a jumping paper carriage in calculating machines, comprising stops provided on the drum for the locking and release thereof in the working positions of the counting mechanisms, the said drum stops being arranged in spiral steps round the axis of the drum, a common abutment adapted to co-operate with the drum stops for checking the movement of the drum, the said common abutment being displaceable in a direction substantially radial in relation to the drum, a rotatable and axially displaceable screw spindle adapted when rotated to displace the common abutment relatively to the drum, a spring tending to resist axial displacement of the said spindle, and rider stops mounted on the paper carriage in positions corresponding to column subdivisions, the said rider stops being adapted to rotate the said spindle when the paper carriage executes its jumping movements.

5. A feeding device for the storage counting mechanisms arranged on the periphery of a drum rotatable under the control of a jumping paper carriage in calculating machines, comprising stops provided on the drum for the locking and release thereof in the working positions of the counting mechanisms, the said drum stops being arranged in spiral steps round the axis of the drum, a common abutment adapted to co-operate with the drum stops for checking the movement of the drum, the said common abutment being displaceable in a direction substantially radial in relation to the drum, a rotatable and axially displaceable screw spindle adapted when rotated to displace the common abutment relatively to the drum, a spring tending to resist axial displacement of the said spindle and of the common abutment, a rotatable shaft, toothed wheels for transmitting motion from the said rotatable shaft to the screw spindle that displaces the common abutment, a star wheel secured to the rotatable shaft, and rider stops mounted on the paper carriage in positions corresponding to column subdivisions,

the said rider stops being adapted to rotate the star wheel when the paper carriage executes its jumping movements.

6. A feeding device for the storage counting mechanisms arranged on the periphery of a drum rotatable under the control of a jumping paper carriage in calculating machines, comprising stops provided on the drum for the locking and release thereof in 10 the working positions of the counting mechanisms, the said drum stops being arranged in spiral steps round the axis of the drum, a rotatable screw spindle extending in a substantially radial direction in relation to the 15 drum, an internally screw-threaded slide meshing with the screw spindle, a guide adapted to prevent the slide from rotating with the spindle, a common abutment adapted to co-operate with the drum stops for 20 checking the movement of the drum, the said common abutment being so mounted in the slide as to be displaceable therein transversely to the screw spindle besides being displaceable with the slide along the spindle, a resilient 25 member adapted to bear, in all positions of the common abutment, against the end of the said abutment opposite to the end against which the drum stops strike, and rider stops mounted on the paper carriage in positions 30 corresponding to column subdivisions, the 35 said rider stops being adapted to rotate the said spindle when the paper carriage executes its jumping movements.

7. A feeding device for the storage counting mechanisms arranged on the periphery of a drum rotatable under the control of a jumping paper carriage in calculating machines, comprising stops provided on the drum for the locking and release thereof 40 in the working positions of the counting mechanisms, the said drum stops being arranged in spiral steps round the axis of the drum, a rotatable and axially displaceable screw spindle extending in a substantially 45 radial direction in relation to the drum, an internally screw-threaded slide meshing with the screw spindle, a guide adapted to prevent the slide from rotating with the spindle, a common abutment adapted to co-operate with the drum stops for checking the movement 50 of the drum, the said common abutment being so mounted in the slide as to be displaceable therein transversely to the screw spindle besides being displaceable with the slide 55 along the spindle, a spring tending to resist axial displacement of the said spindle and of the common abutment, a resilient member adapted to bear, in all positions of the common abutment, against the end of the 60 said abutment opposite to the end against which the drum stops strike, a rotatable shaft, toothed wheels for transmitting motion from the said rotatable shaft to the screw spindle that displaces the common abutment, a star 65 wheel secured to the rotatable shaft, and rider

stops mounted on the paper carriage in positions corresponding to column subdivisions, the said rider stops being adapted to rotate the star wheel when the paper carriage executes its jumping movements.

In testimony whereof, I have signed my name to this specification.

HERMANN ANTON RAUH.
